AMMUNITION MAKING MACHINERY

Douglas S. Kuehl, Reading, Mass., assignor to
 Remington Arms Company, Inc., Bridgeport,
 Conn., a corporation of Delaware

Application November 10, 1943, Serial No. 509,814

7 Claims. (Cl. 192—125)

This invention relates to ammunition making machinery, and particularly to a stopping system therefor to prevent damage to the tools of the machine.

In the manufacture of ammunition it is frequently desirable to have a safety means on the assembling machinery to stop the machine in the event a component is absent at a particular station of the machine. The usual machine has a transfer means to move the component step by step from station to station and the absence of a component at a station may be caused by the component being grasped by the forming tool or die at a station so that the component is not carried to the next station by the transfer means. When this occurs, another piece may be carried to said station and the tool, upon its next reciprocation, will carry a second component into the die with a resultant destruction or damage of the tools or machine.

As a specific example, the present device can be applied to a bullet assembly machine. The other objects of the invention will appear from the following description and drawings which are to be considered as merely illustrative and not limited.

Fig. 1 shows a front diagrammatic view of a bullet assembly machine.

Fig. 2 is a perspective fragmentary view as a component is being transferred to the next station by the transfer means.

Fig. 3 is a fragmentary perspective view of the stop means in its operative position when a component is absent from the transfer means and after the forming tool has been reciprocated upwardly.

Fig. 4 is a fragmentary perspective view after a component has been removed from the transfer means and the stop arm is held by the transfer bar, the reciprocating forming tools being in their upper position.

Fig. 5 is a diagrammatic view of a wiring system which may be used.

In Fig. 1, the main frame of the machine is indicated at 10, with the various operating tools shown generally at 11 for performing a sequence of operations upon the component. For example, in the assembly of small arms armor piercing projectiles, the components are fed at the various stations and the tools perform the assembling operations thereon. An armor piercing projectile, such as the caliber .50, may comprise a jacket which is shaped from a cup fed to the machine, a core, and a lead point for the core. These various elements are introduced into the

machine in their proper locations and the tools assemble and form the projectile. The tools 11 may be carried by the reciprocating means or gate 12 which is driven by the motor 13. The transfer bar 14 has guides 15. The transfer bar serves to move the bullet elements from left to right and under the various tool or operating stations, said bar being reciprocated by suitable driving connections (not shown) operated by the main drive 13 in synchronism with the gate 12. Dies for the forming of the components may be located underneath the transfer means in the various holding blocks 16. Some of these dies may have ejectors therein to raise the component up to the level of the transfer bar. The punches may also have ejection means therein which are automatically operated to eject the articles from the punch. The precise details of the tools are immaterial and not a part of the present invention. It is to be understood that various combinations and sequences may be used and that the bullet can be assembled completely in one machine or the operation may be performed in two machines. As an example, the tools and stations from 17 to 22 of Fig. 1 may serve to deliver the various components of the projectile and assemble the same, and tools at stations 23 to 26 may be used for shaping or tapering the projectile in any well-known manner. Station 27 may be known as the "correction station" where the heel closure and the projectile are brought to correct length. It is not desirable to have an ejector in the bottom die at this station and there is also a danger that the ejector in the top punch may break, thereby allowing a projectile to become lodged in the die or punch. When this occurs, another projectile will be carried into place under the correction punch and when the correction punch descends in the next reciprocation, a jam or breakage will occur due to the presence of the previous projectile at this station. At the correction punch station, the tapered heel forming portion of the reciprocating punch 27 will serve to draw the projectile upwardly out of the bottom forming die.

The stop means of the present invention serves to inspect and determine whether or not the projectile has been carried upwardly with the plunger out of the transfer means or remains in the forming dies, and if this occurs, to stop the machine. The transfer mechanism reciprocates in a substantially horizontal plane and comprises the channel shaped bar 14 with legs 29 and 30. The bar is guided in bearings 15 having upstanding portions 31, 32, and 33. The specific form of the

bearings or guides may be changed as desired. The transfer bars carry suitable fingers 34 which are pivotally mounted in apertures 35 in the transfer bar 14. Springs 36 may be located behind each of the transfer fingers to allow pivotal action of the fingers as the transfer bar moves to the left to engage the component at the preceding station. When the tools have been reciprocated downwardly so that each engages one of the components being operated upon, the transfer bar may move to the left so that each pair of fingers will grasp or be in a position to grasp the next succeeding component after the tool at the preceding station has completed its operation and has reciprocated to its upper position. The springs behind the transfer fingers allow the fingers to pivot as they slide past the components or the tools, the components at the moment being held as they are being operated upon by their tools. After the reciprocating tools have been raised, the transfer bar moves to the right and thereby carries the components from each of the stations to the next succeeding station.

In Fig. 2, the transfer bar is shown as it is moving and carrying a projectile 37 from under the correction punch 27 to the ejection punch station 28.

In Fig. 4 the component 38 is shown located under the correction punch 27 as the punch is descending. A stop switch such as a "Microswitch" or any other type switch, is located at 39. This switch has an operating button 40 which may be contacted by the pivoted lever 41, said lever being pivoted at 42. A spring 43 tends to rotate the stop lever 41 in a clockwise direction (Fig. 2) thus tending to move it against or toward the button 40. When a projectile is in the transfer mechanism, said projectile will contact the pivoted arm 41 and hold the same away from the switch operator. As the transfer bar moves further to the right and toward the ejection punch 28, the stud 45 will contact the pivoted arm 41 (see Fig. 4), or contact will be made therewith after the end 46 of the operator 41 slides by projectile 38'. As the transfer bar moves to the left while the punches are moving downwardly to operate on the components or eject the same, the pivoted arm 41 will move in a clockwise direction until it strikes the correction punch 27 or a projectile 38 in the transfer means. Under normal operation, the correction punch will be contacted by the lever 41 and the transfer bar will continue to move to the left until the fingers are positioned under the preceding station. The stud 45 will then be withdrawn from contact with 41 so that when the punch 27 moves upwardly again, the absence of a projectile in the fingers will allow lever 41 to move in clockwise direction and operate switch 39, such as shown in Fig. 3. The absence of a projectile in the transfer bar may be the result of the projectile being carried upwardly by the punch 37 or remaining in the die under the transfer bar. In either event, the absence of a projectile in the transfer means will cause the switch 39 to be operated and thus stop the machine to prevent a second projectile being brought under the punch.

Referring to Fig. 5, the pivoted arm is shown at 41, and plunger 40 with switch diagrammatically indicated at 39. The switch 39 is normally closed and the circuit to the motor or control therefore energized. It is to be understood, of

course, that other types of switching circuits may be used.

The present invention provides a stop means for stopping an ammunition assembly machine when an ammunition component is absent from the transfer bar and may be applied to various types of machines for assembling ammunition components.

The invention is not limited to the details described and illustrated but is to be construed to cover all equivalent devices falling within the scope of the appended claims.

What is claimed is:

1. In an ammunition component assembly machine having an operating station: a tool at said operating station; driving means for the machine; reciprocating transfer means having component positioning means thereon for transferring components to and from said station; a control switch for said driving means; an operator for said control switch; means on said transfer means to positively hold said operator from contacting said switch until said transfer means has returned from a reciprocatory transfer movement and said tool is operating on the component at the operating station; and means on said operator to urge the same toward switch operating position to operate said switch to stop the machine in the absence of a component for transfer away from said operating station.

2. In an ammunition component assembly machine having an operating station: means to operate on a component at said station; reciprocating transfer means having component positioning means thereon for transferring components to and from said station; driving means for said machine; a control switch for said driving means; an operator for said control switch; means on said transfer means adapted to positively hold said operator from contacting said switch until after said means to operate on a component has started an operation thereon; and means to urge said operator to switch operating position to stop the machine in the absence of a component in position in the transfer means after an operation has been performed on said component.

3. In an ammunition component assembly machine having an operating station: a tool to operate on a component at said station; a reciprocating transfer bar having component positioning means thereon for transferring components to and from said station; driving means for said machine; a control switch for said driving means; an oscillatable pivoted operating arm for said control switch; means on said transfer means adapted to positively hold said arm away from said switch until after said tool has started an operation on a component and is in a position to hold said arm away from the switch; and yieldable means to oscillate said arm to switch operating position for stopping said machine in the absence of a component in the transfer bar after the tool has operated on said component.

4. In an ammunition component assembly machine having an operating station: a reciprocating tool for operating on a component at said station; a reciprocating transfer bar having component holding means for transferring components to and from said station; driving means for the machine; a control switch for said driving means; an oscillatable pivoted lever having one portion overlying the path of travel of a component in said transfer bar and one portion adapted to operate said switch; holding means on

said transfer bar adapted to oscillate said lever as the bar reciprocates to transfer a component away from said station, said holding means being located to allow operation of said switch by said lever in the absence of a component in the transfer bar after a reciprocation of said tool.

5. In an ammunition component assembly machine having a plurality of operating stations; a reciprocating tool for operating on an component at one station thereof; a reciprocating transfer bar having component positioning means for transferring components step by step from station to station; driving means for said machine; a control switch for said driving means; an oscillatable pivoted lever having one portion overlying the path of travel of components in said transfer bar away from said tool; holding means mounted on said transfer bar adapted to hold said lever until said tool has started a reciprocation and stands in the way of further movement of the lever; and means to urge said lever toward switch operating position to stop said machine in the absence of a component in the transfer means after a reciprocation of said tool.

6. In a bullet assembly machine having a plurality of stations; a reciprocating transfer bar for moving components step by step from station to station, said bar having component positioning and grasping means thereon; a die at one of said stations; a reciprocating forming tool at said last mentioned station for carrying a component from the transfer bar into said die; driving means for said machine; a control switch for said driving means; an oscillatable pivoted lever having one portion overlying the path of travel of a

component in said transfer bar and oscillatable by a component being transferred from said station; a stud mounted on and reciprocable with said transfer bar, said stud being located to hold said lever from switch operating position until said tool has reciprocated into a position blocking the lever; and means to urge said lever toward switch operating position to stop the machine in the absence of a component in the transfer bar after a reciprocation of said tool away from said die.

7. In a bullet assembly machine having a frame and a plurality of operating stations; a reciprocating transfer bar for moving components step by step from station to station, said bar having component positioning and grasping means thereon; a die at one of said stations; a reciprocating forming tool at said last mentioned station for carrying a component from the transfer bar into said die; driving means for said machine; a control switch for said driving means; an oscillatable lever pivoted on the frame adjacent said last mentioned station, one end of said lever being located in the path of travel of a component in said transfer bar away from said station and the other end of said lever being adapted to operate said switch; a stud on said transfer bar for holding said lever from operating said switch until the forming tool has reciprocated downwardly; and a spring tending to rotate said lever to switch operating position and operable in the absence of a component in the transfer bar after said forming tool has moved upwardly.
